WARREN T. HUNT, OF TOLEDO, OHIO, ASSIGNOR TO THE WILLYS-OVERLAND COMPANY,
OF TOLEDO, OHIO, A CORPORATION OF OHIO

CARBURETOR CHOKE CONTROL

Application filed September 14, 1927. Serial No. 219,462.

My invention relates to carburetors for internal combustion engines commonly employed in automobiles, and it has particular relation to the construction and operation of 5 the choke valve.

It is commonly recognized that one of the more desirable methods of starting a gasoline engine which is relatively cool, is to enrich the carburetor mixture for a short period of 10 time until the combustion chamber attains its normal operative temperature. To this end most carburetors are provided with a choke valve which the driver can operate by actuating a choke control generally positioned near 15 the steering wheel. After the engine begins to run smoothly and the necessity for the rich mixture no longer obtains, it is incumbent upon the driver to return the choke to its normal position. Failure to do so results in 20 overheating of the engine, fouling of the spark plugs, as well as an excessive consumption of fuel.

Not infrequently it happens that the jostling of the car causes the choke valve to close, 25 at least partially, without being noticed by the operator, until after the engine begins to operate irregularly. According to the present invention, these failings and shortcomings are overcome, thus one object of the invention 30 is to provide a carburetor choke valve which displays no tendency to close by reason of the jostle and shock that is normally imparted thereto.

Another object of the invention is to provide 35 a carburetor structure wherein the choke valve will return to its open position automatically and without the attention of the driver.

A further object of the invention is to provide 40 a carburetor structure wherein the choke valve will return to its open position automatically under normal running conditions.

In so far as the elements of my improved carburetor are novel, the invention contemplates 45 a new method of operating internal combustion engines, according to which the choke valve is opened gradually by the vibration of the engine or the motor car in which it is installed. A better understanding of 50 how these and other objects of the invention

may be realized can be had by referring to the accompanying drawings, in which

Figure I is an elevational view of an embodiment of the invention which may be preferred, and

Fig. II is a plan view partly in section, of the structure illustrated in Fig. I.

In practicing my invention, there is provided a carburetor shell or casting 10 of conventional or approved design, which includes an air intake opening 11 that is controlled by a choke valve 12. The valve includes a shaft 13 which is pivotally mounted in the casting and is provided at one end with a control arm 14 that is operated by means of a wire 15 from the driver's seat. Between the actuating arm and the carburetor casting, a second arm 17 is interposed which is secured rigidly to the shaft and includes a weight 18 at its outer extremity. The other end of the shaft is provided with a coil spring 19 and a nut 20 which is tightened to secure the desired amount of friction between the weight arm 17 and the elements adjoining thereto, particularly the casting 10. A lug 22 formed integrally with the carburetor casting adapted to engage with a projection 23 that forms a part of the actuating arm 14, the relation of the parts being such that the projection contacts with the lug 22 in the open position of the choke as shown by full lines of Figure 1.

It will be observed that in its open position the weight is prevented from pivoting downwardly in a counterclockwise direction by the pawl which is in engagement with the lug; whereas, in its closed position the weight is prevented from turning in a clockwise direction by reason of the valve member 12 within the intake portion of the casting. The tendency of the choke valve to assume its wide open position will depend upon the friction between the pivotal weight arm member 17 and the adjoining casting member 10. The adjustment may be made whereby the valve will not reach its wide open position until the automobile has traveled some distance and the engine probably has its temperature materially increased.

From a consideration of the structure, it will be apparent to those skilled in the art

that a carburetor of my design provides a gas mixture whose composition may be varied manually and which will have a tendency to revert to normal mixture. It will also be apparent that the weight arm functions to maintain the choke in an open position during the normal operation of the engine, and also that the normal shock which the car encounters, acts to return the choke valve to its wide open position without any attention from the driver whatsoever.

Although there is illustrated but a single embodiment of my invention, it will be apparent that other embodiments may be constructed with the same principles, and I desire therefore that it be limited only as indicated in the appended claims.

I claim:

1. In a carburetor a pivotal choke valve provided with an unbalanced weight adapted to constantly urge the valve into its open position.
2. In a carburetor a pivotal choke valve provided with an unbalanced weight adapted to urge the valve into its open position, and friction means for regulating the pivotal movement.
3. In a carburetor a choke valve provided with a weighted pivotable lever arm secured to the choke valve adapted to constantly urge the valve into an open position.
4. In a carburetor a choke valve including a lever arm cooperatively pivotal with the valve adapted to urge the valve into an open position, and adjustable friction means for controlling the tendency of the valve to pivot.
5. In a carburetor a rotatable choke valve, means for manually operating said valve, a stop for limiting the movement of the valve in one direction, and a weighted lever secured to the valve in position to rotate the same against the stop.

In testimony whereof, I affix my signature.

45

WARREN T. HUNT.
